UNITED STATES PATENT OFFICE

154,887

DESIGN FOR A COMBINED FINGER RING AND WATCH

Bert Silverman, New York, N. Y.

Application June 5, 1948, Serial No. 146,776

Term of patent 3½ years

(Cl. D45—10)

To all whom it may concern:

Be it known that I, Bert Silverman, a citizen of the United States, residing at New York, Bronx County, New York, have invented a new, original, and ornamental Design for a Combined Finger Ring and Watch, of which the following is a specification, reference being had to the accompanying drawing, forming part thereof, in which

Fig. 1 is a top plan view of a combined finger ring and watch, showing my new design, and

Fig. 2 is an edge elevational view thereof.

I claim:

The ornamental design for a combined finger ring and watch, as shown.

BERT SILVERMAN.
